GEORGE BODIN, OF CHICAGO, ILLINOIS, ASSIGNOR TO GOODMAN MANUFACTURING COMPANY, OF CHICAGO, ILLINOIS, A CORPORATION OF ILLINOIS

MINING-MACHINE TRUCK

Application filed July 6, 1926. Serial No. 120,575.

This invention relates to a novel improvement in mining machine trucks, adapted for transporting coal cutting mining machines in mines.

- 5 The principal object of this invention is to provide a simple and efficient means for transporting and maneuvering a mining machine beyond the end of a mine track, as for instance, along the floor of a mine room.
- 10 A further object of the invention is to provide a truck sufficiently low in order that a mining machine may be propelled about mine rooms in mines where the coal seams are relatively thin. Another object is to
- 15 provide the truck with steering rods outside thereof, to enable the loading and unloading of the mining machine without interfering with the steering mechanism.

The invention will best be understood by reference to the accompanying drawings, in which:

Figure 1 is a top plan view of a truck with the mining machine removed therefrom, and illustrating the steering device arrangement;

Figure 2 is a view of the truck in side elevation, showing a mining machine thereon in dotted lines;

Figure 3 is an enlarged partial side elevation of the truck with parts broken away and in section to more clearly illustrate the steering mechanism.

Figure 4 is a transverse section of the steering beam and appurtenances, taken on line 4—4 of Figure 1;

Figure 5 is a transverse section through pivot connection of the steering beam, taken on line 5—5 of Figure 4; and

Figure 6 is an enlarged transverse section through the front axle, taken on line 6—6 of Figure 1; and

Figure 7 is an enlarged partial side elevation of the forward portion of the truck with parts broken away and in section showing the details of the front axle construction.

I have illustrated my invention as applied to a truck for transporting a mining machine from one portion of the mine to another. The main entries of a mine are usually provided with track, over which a min-

ing machine and truck may be readily transported, but in a great number of instances, it is desirable to transport the mining machine a considerable distance beyond the end of the tracks, up to the working face, as for example in mines where it is not deemed advisable or economical to extend temporary tracks into such mine rooms. In such cases it has heretofore been necessary to unload the mining machine from the truck at the entrance to the rooms, and drag it bodily to the working face by means of crow bars or the like, or by power driven draft ropes carried by the machine, and anchored at a distance therefrom.

In carrying out my present invention, I provide a truck mounted on suitable tractor type wheels and including an improved steering device, which permits the mining machine to be speedily delivered to the working face, over mine floors without tracking, and to be guided or turned at will for loading or unloading the mining machine at any desired point.

My improved type of mining machine truck is particularly adaptable for transporting mining machines into mine rooms where scraper loading units are used, and the extension of tracks in the rooms is therefore rendered impossible under usual mining conditions. Since the truck is especially equipped for maneuvering on mine floors without tracking, it is possible to travel both to and from the working face, or to a "break through" in mine rooms, and also in case of necessity to a convenient out of the way location, thereby permitting the scraper loading element to remain in position in the room neck on the track.

The ruggedness and durability of construction, in conjunction with the simplicity of operation, permits the truck to be handled with ease.

Referring now in detail to the drawings, a mining machine truck is indicated at 1, provided with a body portion 2, having a pair of longitudinally disposed side members 3, 3, attached thereto, acting as guides when loading and unloading a mining machine. Said body portion is provided with

the usual drop front 4, pivotally supported at the forward end thereof to receive a mining machine 11 (see Figure 2) of the usual type which is drawn up on said drop front 5 on to the truck by means of its draft ropes in the usual manner. The rearward portion of said body is provided with a pair of suitable tractor type rear wheels 5, 5, disposed inside of the combination frames and 10 guards 6, 6, which have rigid connection to the sides of the body. Each of said combination frames and guards are provided with a pair of internal hub projections 7, 7, on the sides thereof, adapted to support 15 transversely disposed stud axles 8, 8. A pair of sprockets 10, 10, are fixed to rotate and drive the rear wheels 5, 5. Said sprockets are operatively engaged through 20 suitable chains 13, 13, to a second pair of drive sprockets 14, 14, forming part of the usual truck driving mechanism generally indicated at 60 adapted to be driven by a motor 12 of the mining machine 11 through 25 a coupling pin 12^a in the usual manner when said mining machine is mounted on 30 the truck. Said truck driving mechanism comprises a worm 61 driven by the coupling pin 12^a which in turn drives a worm wheel 62 on a shaft 63 for driving the sprockets 35 14, 14.

From the foregoing explanation it may readily be seen that the said rear wheels receive the necessary power to propel the said truck about the mine room.

The steering device for the truck embodies several novel features. In the embodiment illustrated in Figure 1, I have shown an arrangement, indicating the steering wheel with appurtenances to be situated 40 at one side of the truck, herein the right hand side.

A steering wheel 17, is provided with a loosely mounted handle 18, at a point near the outer circumference thereof. Said steering wheel has a hub extension 19, cast 45 integral therewith, and is rigidly attached by means of a key to the rearward or unthreaded end portion of a longitudinally disposed screw 20. The unthreaded portion 50 of said screw is afforded support forward of said steering wheel by means of a flanged journal 21, substantially secured by suitable means to an angle iron 22, which herein forms the rear end of said truck body. A 55 collar or spacer 23 is loosely mounted on the screw intermediate the said hub extension of the steering wheel and said flanged journal. A trunnion nut 24, having threaded engagement on said screw, is provided 60 with a pair of stud projections 25, 25, formed integral with said nut, and disposed in opposite relation to each other, and on the vertical axis of said trunnion nut. Said stud projections engage apertures in the 65 trunnion nut bracket 28, and in the steer-

ing beam 29, respectively. Said trunnion bracket and steering beam are provided with suitable depressions 30, 30, at a point in line with the trunnion nut, so as to form a guide to prevent radial movement of the 70 trunnion nut about the vertical axis of the stud projections.

The steering beam is transversely disposed and pivotally mounted on a pivot pin 31, on the longitudinal center line at the 75 rearward end of the truck, intermediate a tongue extension 32, and an angle clip support 33. Said tongue and angle clip are rigidly secured to the angle iron at the rear of said truck, and are vertically spaced 80 by a shim or filler bar 34, to provide free rotatable movement of the steering beam about said pivot pin.

The various members of the steering apparatus on each side of the truck are similar 85 in construction and operation, therefore the description and numbering of the parts for one side will suffice and apply to both.

The end portions of the steering beam project beyond the lateral sides of the truck. 90 Each of the end portions are provided with an offset portion 35. A strap 36 is suitably attached at the end of said steering beam directly over the offset portion, thereby forming a clevis. Said clevis is provided 95 with a pivot pin 37 depending therethrough and pivotally securing therein the flattened end portion 38 of a steering rod 39. Said steering rods are longitudinally disposed outside of the lateral boundaries of the 100 truck to that the height of the truck may be kept at a minimum. The forward end of said steering rod is also flattened at 40, and is supported in a clevis 41, of a clevis nut 42. The forward end 40 is pivotally 105 mounted on a pivot pin 43 in said clevis. The clevis nut is provided with a recess 44 on the side opposite the clevis. The recess of the clevis nut is inwardly threaded for engagement on the threaded portion of a 110 front axle 45. Said front axle is formed integral with the axle bracket 46. The front axle is provided with a loosely mounted tractor type wheel 47, forming the front 115 supporting wheels for the truck.

The axle bracket is provided with a vertical boss portion adapted for pivotally mounting between a pair of horizontally disposed lug projections 50, 50, by means of a pivot pin 51, which is rigidly secured to said boss portion. The pivot pin 51 is permitted to freely rotate in said lugs, thereby affording free turning of the entire wheel and axle. The lug projections are formed integral with a frame bracket 53, which is 120 rigidly secured to the body of said truck.

On the upper end of the vertical sides of said body, I provide studs 54, 54, vertically disposed rearward of said steering beam, as a means to limit the radial movement of 125

the steering beam, and thereby preventing either of said front wheels from striking the body of the truck. The steering beam is partially supported and guided on the upper edges of said sides and is therefore always assured of being in line to engage the studs.

The use and operation of a truck as herein described will be readily understood by those skilled in the art.

Although I have shown and described one form in which my invention may be embodied, it will be understood that the construction and arrangement of the various parts may be altered without departing from the spirit and scope thereof. I do not therefore wish to be construed as limiting myself to the specific construction illustrated herein excepting as may be specifically limited in the appended claims.

I claim as my invention:

1. A mining machine truck comprising a body portion and front and rear supporting wheels, driving mechanism for said rear wheels adapted to be detachably connected with the motor of the mining machine, means supporting said front wheels for steering movement, controlling members connected at the outside of said steering wheels extending to the rear of said truck, a transversely disposed steering beam pivotally mounted at the rear of said truck and connected at opposite ends with said controlling members, and screw means carried on said body portion adapted to actuate said steering beam.

2. In a mining machine truck, a body portion, supporting wheels for said body portion comprising a pair of traction wheels and a pair of steering wheels, supporting axles for said traction wheels and said steering wheels, said supporting axles being above the bottom portion of said body portion and said supporting axles for said steering wheels being movable about a vertical pivotal axis on the outer sides of said body portion, members connected with the outer portions of the axles for said steering wheels for moving said axles about their vertical pivotal point, said connection members extending rearwardly on the outer side of said traction wheels to the rearward portion of said truck, a transversely disposed steering beam pivotally mounted at the rear of said truck and connected at opposite ends with said connecting members for moving said connecting members and thus moving said axles around their vertical pivotal point.

3. In a mining machine truck, a body portion, a mining machine slidable thereon, supporting wheels for said body portion comprising a pair of traction wheels and a pair of steering wheels, driving means for said traction wheels connectible with a mo-

tor on said mining machine, supporting axles for said traction wheels and said steering wheels, said supporting axles being above bottom portion of said body portion and said supporting axles for said steering wheels being movable about a vertical pivotal axis on the outer sides of said body portion, members connected with the outer portion of the axles of the forward steering wheels, said members extending to the rearward portion of said mining machine, and a transversely disposed steering beam pivotally mounted at the rear of said truck and connected at opposite ends with said connecting members for moving said connecting member and thus moving said steering wheels about their pivotal axis.

4. In a mining machine truck, a body portion, a mining machine slidable thereon, supporting wheels for said body portion comprising a pair of rearward traction wheels and a pair of forward steering wheels, driving means for said traction wheels connectible with a motor on said mining machine, supporting axles for said traction and steering wheels, said supporting axles being above the bottom portion of said body portion and said supporting axles for said steering wheels being movable about a vertical pivotal axis on the outer sides of said body portion, members connected with the outer portion of the axles for said steering wheels for moving said axles about their vertical pivotal point, said connecting members extending rearwardly on the outer side of said traction wheels to the rearward portion of said truck, a transversely disposed steering beam pivotally mounted at the rear of said truck and connected at opposite ends with said connecting members, for moving said connecting members, and screw means carried on said body portion adapted to actuate said steering beam.

5. In a mining machine truck, a body portion, a mining machine slidable thereon, supporting wheels for said body portion comprising a pair of rearward traction wheels and a pair of forward steering wheels, driving means for said traction wheels connectible with a motor on said mining machine, means supporting said front wheels for steering movement, and means for steering said front wheels from the rearward portion of said truck comprising controlling members connected at the outside of said steering wheels and extending beyond said traction wheels to the rear of said truck.

6. In a mining machine truck, a body portion, a mining machine slidable thereon, supporting wheels for said body portion comprising a pair of rearward traction wheels and a pair of forward steering wheels, driving means for said traction

wheels connectible with a motor on said mining machine, means supporting said front wheels independently at opposite sides of said body portion for steering movement, and means for steering said front wheels from the rearward portion of said truck comprising controlling members connected at the outside of said steering wheels and extending beyond said traction wheels to the rear of said truck.

7. In a mining machine truck, a body portion, a mining machine slidable thereon, supporting wheels for said body portion comprising a pair of rearward traction wheels and a pair of forward steering wheels, driving means for said traction wheels connectible with a motor on said mining machine, means supporting said front wheels independently at opposite sides of said body portion for steering movement, and means for steering said front wheels from the rearward portion of said truck comprising controlling members connected at the outside of said steering wheels and extending beyond said traction wheels to the rear of said truck, and a transversely disposed steering beam pivotally mounted at the rear of said truck and connected at opposite ends with said controlling members.

8. In a mining machine truck, a body portion adaptable to receive a mining machine thereon, supporting wheels for said body portion comprising a pair of rearward traction wheels and a pair of forward steering wheels, driving means for said traction wheels connectible with a mining machine motor, means for independently supporting said forward steering wheels for steering movement, and means for steering said forward wheels from the rearward portion of said truck comprising a rigid controlling member connected to the outside of each steering wheel and extending beyond said traction wheels to the rear of said truck, said controlling members being located beneath the top portion of said steering and traction driving wheels.

9. In a mining machine truck, a body portion adaptable to receive a mining machine thereon, supporting wheels for said body portion comprising a pair of rearward traction wheels and a pair of forward steering wheels, driving means for said traction wheels connectible with a mining machine motor, means for independently supporting said forward steering wheels for steering movement, and means for controlling the steering movement of said forward wheels from the rearward portion of said truck comprising a rigid controlling member connected to the outside of each steering wheel beneath the top portion thereof and extending beyond said traction wheels to the rear of said truck, and a transversely

disposed steering beam pivotally mounted at the rear of said truck and connected at opposite ends with said controlling members.

Signed at Chicago, in the county of Cook and State of Illinois, this 30th day of June, 70
A. D. 1926.

GEORGE BODIN.
